CLAIM

The ornamental design for an anti-rail rollover device, as shown and described.

DESCRIPTION

FIG. 1 is a perspective view of an anti-rail rollover device showing our new design according to a first embodiment; FIG. 2 is a right view thereof; FIG. 3 is a left view thereof; FIG. 4 is a rear view thereof; FIG. 5 is a front view thereof; FIG. 6 is a top view thereof; FIG. 7 is a bottom view thereof; FIG. 8 is a perspective view of an anti-rail rollover device showing our new design according to a second embodiment; FIG. 9 is a right view thereof; FIG. 10 is a left view thereof; FIG. 11 is a rear view thereof; FIG. 12 is a front view thereof; FIG. 13 is a top view thereof; and, FIG. 14 is a bottom view thereof.

The broken line showings of FIGS. 1, 5, 6, and 7 are environmental only and not part of the claimed design.

1 Claim, 14 Drawing Sheets
